CLAIM

The ornamental design for a confection, as shown and described.

DESCRIPTION

FIG. 1 is a top, front, left side perspective view of a first embodiment of a confection of the present invention.

FIG. 2 is a lower side view of the confection of FIG. 1 front elevation view thereof.

FIG. 3 is a rear elevation view thereof.

FIG. 4 is a right side elevation view thereof.

FIG. 5 is a left side elevation view thereof.

FIG. 6 is a top plan view thereof.

FIG. 7 is a bottom plan view thereof.

FIG. 8 is a top, front, left side perspective view of a second embodiment of a confection of the present invention.

FIG. 9 is a front elevation view thereof.

FIG. 10 is a rear elevation view thereof;

FIG. 11 is a right side elevation view thereof.

FIG. 12 is a left side elevation view thereof.

FIG. 13 is a top plan view thereof; and,

FIG. 14 is a bottom plan view thereof.

The broken lines in FIGS. 1, 5 and 6 illustrate portions of the confection that form no part of the claimed design.

1 Claim, 8 Drawing Sheets(56)
